John W. Swan,
Milans & Milans, Attorneys:

UNITED STATES PATENT OFFICE.

JOHN W. SWAN, OF STAMFORD, CONNECTICUT.

CARBURETOR.

Application filed September 25, 1919. Serial No. 336,284.

This invention relates to improvements in carburetors, and is of the general type disclosed in my Patent No. 1,260,594, granted March 26, 1918.

- 5 The principal object of my invention resides in the provision of a fuel and air distributing valve so constructed that the incoming air to the carburetor chamber will be under a high velocity.
- 10 A further object resides in the provision of an air and fuel distributing valve having a Venturi tube extending therethrough, said tube being so constructed that the air will pass therethrough under high velocity and the fuel will be atomized to be mixed with the air.

Another object consists in the provision of a throttle valve and a fuel and air distributing valve adapted to be operated in unison, the air and fuel distributing valve having a Venturi opening or tube through which the air passes under high velocity to suck in and atomize the fuel, said Venturi tube being positioned below the throttle valve.

In the accompanying drawings I have shown the preferred embodiment of the invention, but I wish it to be distinctly understood that many changes can be made without departing from the spirit thereof.

In the drawings:

Figure 1 is a side elevation of a carburetor constructed in accordance with the present invention.

35 Fig. 2 is a vertical section.

Fig. 3 is a detail vertical section on an enlarged scale of the air and fuel mixing chamber and valve parts directly associated therewith.

40 Fig. 4 is a transverse section of the air and fuel valve.

Referring now more particularly to the drawings wherein like reference characters indicate corresponding parts, the numeral 1 designates a carburetor which may be of any desired construction, although preferably of the type disclosed in my Patent No. 1,260,594. Fuel is introduced to the float chamber 2 of the carburetor through the fuel passage 3 controlled by the valve 4 mounted for a reciprocating movement therein by reason of the spindle 5 passing through an aperture 6 in a portion of the carburetor, the valve being operated by the float 7 which, of course, rises and falls in

keeping with the level of the fuel in the float chamber 2.

Leading from the float chamber is the fuel conducting conduit 8, extending upwardly at an angle thereto into the side wall of the air passage 9 the wall of said air passage having a suitable chamber 10 formed on one side and normally closed by the threaded closure 11 and adapted to receive the fuel passing through the chamber thereto. Transversely mounted within the passage 9 is the rotatable fuel distributing and air controlling valve 12 which is preferably of the butterfly type. The valve is formed with flanged portions of annular 70 formation as indicated by the reference character 14 to position the valve in the passage 9 to prevent a lateral movement thereof during the opening and closing of the valve and extending beyond the face of 75 the right hand flange is a hub 13 for a purpose which will later appear. One end portion rests against its seat 15 in the side wall of the passage, and the other abuts against the hub of the closure plate 16 disposed over 80 the opening in the passage through which the valve is inserted and held in position by the screws 17. A tubular bore 18 is formed centrally of the valve, the valve also being formed with a transverse bore 19 85 into which is positioned a venturi 20 having the usual restricted intermediate portion 21 and the gradually flaring and widened end portions 22. This venturi is preferably of an appreciable length, intersecting the transfer bore 18 in the valve through which fuel is introduced from the chamber 10, the venturi having a plurality of fuel nozzles 23 located therearound, being fed by gasoline or other fuel entering 90 a circumferential chamber 24 surrounding the feed jets 23 and fed through the transverse opening 18, it being understood that fuel is admitted to the chamber 10 through 95 the supply 8 leading from the float chamber. 100

The valve at its side opposite the bore 18 is also provided with a bore 25 through which the needle valve 26 passes, the function of which is to control the passage of fuel through the transverse feeding bore 18 105 and to vary and regulate the fuel that is discharged through the feeding jets 23 of the venturi. This valve is normally maintained in an open position by the action of the spring 27 surrounding the same and at 110

2
one end pressing upon the hub of the butterfly valve, while the other end engages a shoulder portion 28 of the needle valve itself.

5 As a means for operating this needle valve, a construction disclosed in my patent heretofore referred to is preferably employed and the same may be briefly recited as consisting of a shiftable lever 29 having 10 a socket portion 30 therein receiving the end of the needle valve, the lever at one end bearing against an adjustable guide 31 supported upon the member 32, while the other end of the lever engages a fulcrum 33 which 15 may be adjustable so as to vary the throw of the needle valve upon a shifting of the lever in the manner disclosed in my Patent No. 1,260,594. A valve turning member 34 is detachably secured to the hub 13 of the 20 valve 12 and is formed in its outer face with a guide 35 into which the lever is received so that upon a turning of this member 34 the lever is likewise shifted, riding over the guide 31 and fulcrum 33 so as to operate the 25 needle valve and permit the admission of fuel to the venturi. The valve turning member is formed with an extension 36 which is connected with an operating link 37 extending upwardly for attachment to the throttle valve operating means to be now 30 described.

The enlarged portion 3 of the passage 9 is controlled by a throttle valve 38 extending thereacross and mounted on the shaft 39 for an oscillating movement, the shaft at its outer end being secured to a channeled member 40 to which the operating link 37 is pivotally attached. It will, therefore, be apparent that upon the operation of the 40 throttle valve, which is controlled by the arm 41 the valve turning member 34 is likewise rotated, causing an oscillating movement to be imparted to the fuel and air controlling butterfly valve disposed 45 within the passage 9, and also a shifting of the fuel valve 26. When the throttle valve 38 is slightly shifted upon the starting of an engine, the needle valve is, of course, opened a slight extent to permit a flow of fuel

through the transverse fuel feeding passage 50 in the fuel valve 12, this fuel spraying through the jet openings in the venturi, while the suction of the engine causes a rapid flow of air through the venturi 20 55 instantly bringing about an atomizing of the fuel issuing thereto through the discharge nozzles which atomized fuel then passes on to the engine cylinders. As the throttle valve is further opened, it likewise opens the air and fuel distributing valve 12 60 causing a wider opening of the needle valve controlling the fuel supply, air, however, rushing through the venturi 20 to serve in assisting in atomizing the issuing fuel from the spray 23, while additional air is introduced to intermix with this fuel around the sides of the valve 12.

Having thus described the invention, what I claim is:

1. A carburetor comprising a casing having an air passage therein, a valve mounted in the air passage, a Venturi tube passing entirely through the valve for the passage of air, said tube being perforated at its restricted portion, and means for feeding fuel through the perforations into the tube whereby it is atomized by the air passing therethrough. 70

2. A carburetor comprising a casing having an air passage therein, a valve mounted in the air passage and having a Venturi passage extending therethrough for the passage of air, said venturi having a lateral opening inlet at its restricted portion, and means for feeding fuel through the lateral 85 inlet opening into the Venturi passage. 80

3. A carburetor comprising a casing having an air passage therein, a valve mounted in the air passage and having a Venturi passage for the passage of air, the Venturi passage having a perforated restricted portion, and means for feeding fuel through the 90 perforated restricted portion whereby it is atomized by the air passing through the venturi. 95

In testimony whereof I hereunto affix my signature.

JOHN W. SWAN.
